UNITED STATES PATENT OFFICE.

HARRY L. BORDERS, OF ST. LOUIS, MISSOURI.

KNOCKDOWN CORRUGATED PAPER BOX.

Application filed October 28, 1921. Serial No. 511,143.

To all whom it may concern:

Be it known that I, HARRY L. BORDERS, a citizen of the United States, and resident of the city of St. Louis and State of Missouri, have invented certain new and useful Improvements in Knockdown Corrugated Paper Boxes, of which the following is a specification containing a full, clear, and exact description, reference being had to 10 the accompanying drawings, forming a part hereof.

My invention relates to certain new and useful improvements in knock down corrugated paper boxes, and has for its primary 15 object the construction of a corrugated paper box which may be folded, provided with a hinged lid attached thereto which may be folded out flat on the body of the box for shipping purposes.

20 In the drawings,

Fig. 1 is a plan view of the box collapsed and the lid thereof flattened out and superimposed upon the collapsed box.

Fig. 2 is an edge view of the same.

25 Fig. 3 is a front elevation of the box set up, ready for use.

Fig. 4 is a rear fragmental view illustrating the means of attaching the lid to the box.

30 Fig. 5 is a fragmental transverse section through the lid and the upper portion of the box.

Referring to the drawings,

35 6 indicates one side of the box and 7 indicates two of the bottom flaps.

In the construction of the body of the box there are four side walls, such as 6, the same being made out of a single piece of cardboard, and the opposing ends of the piece 40 of cardboard, being secured together by means of a strip of paper or fabric. The side walls when so constructed are capable of collapsing. The bottom flaps 7 (four in number) are formed integral with the side 45 walls and between the adjacent ends of the flaps, slots or cut away portions 8 are formed so as to permit the ends to be folded inwardly in the bottom when the device is set up for use. In setting up the box for use, 50 two of the opposing end flaps are folded first and between the other two end flaps, and then the outside end flaps are folded upon the first mentioned end flaps, and then by means of a strip of paper or fabric, the outside 55 side end flaps are secured together and the body of the box is set up for use. The sides

and bottom of the box are made of corrugated paper board and the cover or lid 9 is made out of fiber cardboard. The lid 9 is provided with two side flaps 10 having their rear corners cut away as at 11. 12 indicates the folding lines for the side flaps 10. The side flaps are provided with extensions 13 which are adapted to be folded on the transverse folding lines 14. 15 indicates the front flap which is separated from the extensions 13 by means of slots 16. The flaps 13 are provided with studs 17 and the front flaps 15 are provided with sockets 18 adapted to receive said studs. The studs and sockets 70 form a detachable connection between the extensions 13 and the front lid flap 15. By means of this detachable connection, the extensions may be detached from the flap 15 and the lid folded out flat, as illustrated in 75 Fig. 1. When it is desired to set up the lid for use, the extensions 13 are folded under the flap 15 and the studs are inserted in the sockets. In this form the lid is set up and ready for use. The lid 9 is also provided 80 with a rear flap 19 which answers as a hinge member. Said hinge flap is placed along the rear side of the box on the outside and is secured thereto by means of staples 20.

It will be observed from the foregoing description that the body of the box may be knocked down or collapsed, and that the lid may be also knocked down and collapsed and folded on the collapsed box as illustrated in Fig. 1, and by means of such construction a great amount of space is saved in packing and shipping, and further, that the box may be readily set up for use by unskilled labor.

Having fully described my invention, what I claim is:

1. A knock down corrugated paper box having collapsible side walls and collapsible bottom flaps, a lid hingedly secured to the top edge of one of said walls, said lid having a pair of collapsible side flaps provided with collapsible extensions, an intermediate collapsible flap spaced apart from said extensions, a fastener secured to each extension, and a fastener secured to each end of the intermediate flap adapted to be readily engaged with and disengaged from the fasteners carried by the extensions for holding the lid in made up form.

2. A knock down corrugated paper box having collapsible side walls formed from a single piece of material, a pair of opposed flaps adapted to be folded on the inside of

the box and a pair of opposed flaps adapted to be folded upon the first mentioned flaps and mounted transversely with the first mentioned flaps, said pairs of flaps adapted to form the bottom of the box when so folded, a collapsible lid hingedly secured to the piece of material out of which the body of the box is formed, said lid having opposed collapsible side flaps provided with

collapsible extensions, a collapsible intermediate flap spaced apart from the extensions, and a readily attachable and detachable connection between said extensions and the intermediate flap whereby the lid may be readily assembled and collapsed. 10

In testimony whereof, I have signed my name to this specification.

HARRY L. BORDERS.
